UNITED STATES PATENT OFFICE.

ABRAHAM L. A. HIMMELWRIGHT, OF NEW YORK, N. Y., ASSIGNOR TO
THE NEW JERSEY WIRE CLOTH COMPANY, OF TRENTON, NEW JER-
SEY, A CORPORATION OF NEW JERSEY.

CENTERING CONSTRUCTION.

No. 835,524.

Specification of Letters Patent.

Patented Nov. 13, 1906.

Application filed March 29, 1905. Serial No. 262,672.

To all whom it may concern:

Be it known that I, ABRAHAM L. A. HIMMELWRIGHT, a citizen of the United States, residing at New York, county of New York, and State of New York, have invented certain new and useful Improvements in Centering Constructions, fully described and represented in the following specification and the accompanying drawings, forming a part of 10 the same.

This invention relates especially to the construction of fireproof floors, ceilings, arches, and similar structures in which a temporary framework or centering is used to support the material of the structure during the making of the same and during the setting of the concrete or other plastic material, if such plastic materials be used, the object of the invention being to provide a simple, cheap, and efficient centering construction adapted especially for making concrete floors, with the concrete extending downward from the floor-web, so as to cover and fire-proof the lower portions of the beams.

For a full understanding of the invention a detailed description of a construction of the preferred form embodying all the features of the same will now be given in connection with the accompanying drawings, forming a part 30 of this specification, and the features forming the invention then particularly pointed out in the claims.

In the drawings, Figure 1 is a cross-section of a floor with the centering in place, the concrete being omitted at the right to show the construction. Fig. 2 is a section on the line 2 of Fig. 1 looking to the right. Fig. 3 is a section similar to Fig. 1, showing the complete construction with the centering removed and the plaster finish applied. Fig. 4 shows a modified form of centering. Fig. 5 is a detail of the extensible buck or top bar of the centering. Fig. 6 is a perspective view of the clip of Fig. 4.

Referring now particularly to Figs. 1 to 3 and 5, A represents the common flanged beams, and the floor is shown as consisting of the ordinary web of concrete B at the tops of the beams, the bodies of concrete C extending downward along the webs of the beams and around and under the bottom flanges of the beams, so that the beams are covered and protected on their under sides by a substan-

tial layer of concrete. The concrete surrounding the lower flanges of the beams is supported by the clips D, placed on the beam-flanges at suitable distances, so as to permit the concrete to be worked under the beam and around the clips in filling it in. These clips D are preferably of the form shown, being provided with pairs of arms preferably of the form shown, and consist of narrow metal plates extending under the beams and slit at their opposite ends, so as to provide pairs of arms 2 3, extending below the beam, which arms are respectively inclined outward and inward and hooked, as shown, and which arms 2 3 are embedded in the concrete filled in below the beams and strongly support the latter. These clips are used to support the centering as follows: The soffit-board E, made in three parts or slotted at intervals opposite the clips, as preferred, is supported below the beams and clips by hangers, shown as wires 4, looped around the arms 1 of the clips D and extending downward through the soffit-board E and around metal bands 5, which extend across the soffit-board E in line with the clips, the ends of the wires 4 being twisted together below the bands 5, so as to thus support the soffit-board E. These bands 5 are preferably half-round steel rods, nailed or screwed to the bottom of the soffit-board and acting to strengthen, as well as support, the latter. By thus twisting the ends of the wires 4 together the soffit-board E may be drawn up tight against the arms 2 3 of the clips D and the soffit-board thus held rigidly in proper position. Upon the soffit-board E, at opposite sides of the beams, are supported the haunch-boards F of the centering, which extend along the beams and with the soffit-board E form a trough to receive the beam-protection concrete. These haunch-boards F are held in place at their upper edges and the support for the top centering-boards, provided by bucks or top bars G, of such length as to extend between the haunch-boards of successive beams, and these bucks G are provided with metal hooks 6 which hook over the tops of the haunch-boards, the bucks and haunch-boards thus being held rigidly in position, with the haunch-boards at inclines determined by the length of the bucks G. The bucks preferably carry depending braces 7 at opposite ends,

which are nailed to the buck in proper position and against which the haunch-boards F rest, so that the incline of these braces determines the incline of the haunch-boards F, 5 the back being of such length as to hold the braces 7 in position with the haunch-boards F flat against them. The haunch-boards F also are preferably secured to the bands 5 by nailing the ends of the bands 5 which extend above the soffit-board E to the haunch-boards F, as shown at 8 in Fig. 1. Upon the bucks G are laid the centering-boards H, which complete the centering. The bucks G are preferably made extensible, so as to be used in beam-spans of different lengths and for this purpose, as shown, are formed of two bars 10 11, held together by metal bands 12, which are secured to the bars to hold them in adjusted position by nails or screws 9, by 20 removing which the bars may be moved in bands to adjust the length of the bucks, as desired.

The centering having been built as above described and the concrete B C filled in to 25 form the floor and beam protection and allowed to set, the centering is removed simply by withdrawing the nails or screws 8 and cutting the wires 4, which releases the whole centering, allowing it to be removed 30 downward from the concrete, the portions of the wires embedded in the concrete being left therein. As shown in Fig. 3, a finish of 35 plaster may be used on the under side of the concrete, or a suspended ceiling of metallic lathing and plaster may be used, as common in such constructions, and the wires 4 may be cut so as to be used for suspending this ceiling, if desired.

The special construction of the soffit- 40 boards shown in Figs. 1 and 2 and above described is not essential, and the soffit-board may be supported by joists below the board, if preferred, and the clips may be used to support a suspended ceiling.

In Fig. 4 a centering construction is shown 45 which is substantially the same as that shown in Figs. 1 and 2, except that the soffit-board rests on joists 1, and the clips D are provided with arms extending through the soffit-board 50 and forming the hangers which support the joists and provide means for supporting a suspended ceiling, if desired. In this construction the clips D are shown as formed with depending arms 25, forming hangers 55 which extend downward through slots in the soffit-board E and are shown as provided with slots 26, from which the joists are supported by hooks 27, which may be of any suitable form, or wires may be used instead 60 of the hooks. After the floor and soffit protection has been filled in, as previously described, and allowed to set the centering is removed by cutting or removing the clips 27 or other means by which the joists 1 are supported from the arms 25. The ceiling-bars

are then passed through the slots 26, so as to be supported by the clip-arms 25 and the usual metallic lathing of woven wire or perforated metal is supported from the ceiling-bars by ties or otherwise and the plaster of 70 the ceiling applied on the under side of this lathing, as usual in such ceiling constructions.

While the invention is especially intended for use in connection with concrete or similar plastic material, which is to be filled around 75 and under beams or the like, it will be understood that the broader features of the invention are applicable also in building brick, tile-block, or similar structures, the invention providing a simple and efficient centering support by which the centering may readily and quickly be placed in position and removed.

What I claim is—

1. The combination with flanged beams, of 80 clips engaging the bottom flanges on both sides of the beams and having arms extending below the beam, a soffit-board below the beams forming a centering-support, hangers supported by said clips and extending through the soffit-board and by which the 85 soffit-board is supported, and a centering supported on said soffit-board.

2. The combination with flanged beams, of 90 clips engaging the bottom flanges on both sides of the beams having inclined and hooked arms extending below the beam to support a concrete beam-protection, a soffit-board below the beams forming a centering-support, hangers supported by said clips and extending through the soffit-board and by 95 which the soffit-board is supported, and a centering supported on said soffit-board.

3. The combination with flanged beams, of 100 clips engaging the bottom flanges on both sides of the beams and having arms extending below the beam, a soffit-board below the beams forming a centering-support, hangers supported by said clips and extending through the soffit-board and by which the 105 soffit-board is supported, haunch-boards extending along the beam and supported edge-wise on the soffit-board, bars extending between the beams and hooked over the top edges of the haunch-boards, and centering- 110 boards on the bars.

4. The combination with beams A, of clips 115 D on the bottom flanges of the beams having pairs of inclined and hooked arms 2, 3, extending below the beams for supporting the concrete beam protection, soffit-board E below the beams supported against the arms by hangers from the clips and haunch-boards F on the soffit-board at opposite sides of the beam.

5. The combination with flanged beams, of 120 clips engaging the bottom flanges on both sides of the beams and having arms extending below the beam, a soffit-board below the beams forming a centering-support, hangers supported by said clips and extending 125 through the soffit-board and by which the 130

through the soffit-board and by which the soffit-board is supported, haunch-boards extending along the beam and supported edge-wise on the soffit-board, extensible bucks or bars extending between the beams and hooked over the top edges of the haunch-boards, and centering-boards on the bars.

6. The combination with the beams A, of clips on the bottom flanges of the beams, 10 soffit-boards E below the beams, hangers supported by the clips and passing through the soffit-board and secured about supports extending across the soffit-board, haunch-boards F on the soffit-boards, extensible 15 bucks G having hooks 6 and braces 7 connect-

ing the haunch-boards, and centering-boards on the bucks.

7. The haunch-boards F, connected by the extensible buck G, formed with the sliding bars 10, 11, hooks 6 hooked over the top edges 20 of the haunch-boards and braces 7 forming supports for the haunch-boards.

In testimony whereof I have hereunto set my hand in the presence of two subscribing witnesses.

ABRAHAM L. A. HUMMELWRIGHT.
